UNITED STATES PATENT OFFICE

2,614,719

LID ASSEMBLY

Harland W. Whitmore, Kenosha, Wis., assignor
to Motor Products Corporation, Detroit, Mich.,
a corporation of New York

Application September 29, 1947, Serial No. 776,745

6 Claims. (Cl. 220—35)

1

The invention relates to lid or cover constructions designed for use in connection with open top cabinets or receptacles, such as refrigerators.

It is the object of the invention to obtain a construction which combines strength and rigidity with comparatively light weight and good thermal insulating properties.

It is a further object to provide means for securing the lid to hinges at one edge thereof and to an operating handle and locking means at the opposite edge. With these objects in view the invention consists in the construction as herein-after set forth.

In the drawings:

Fig. 1 is a plan view of the lid;

Fig. 2 is a front elevation thereof;

Fig. 3 is a cross section on line 3—3; Fig. 1 showing the attachment means for one of the hinges; and

Figs. 4, 5 and 6 are sections, respectively, on lines 4—4, 5—5 and 6—6, Fig. 1, showing other features of the construction; and

Fig. 7 is an enlarged cross section on line 7—7, Fig. 1.

A is a pressed sheet metal member of substantially rectangular form but with rounded corners, said member including a top portion A' and a depending flange A² extending around all sides thereof. The member A is preferably formed of relatively light gauge metal and to strengthen the same it is provided with transversely extending reinforcement members B. These are preferably of channel cross section and are fashioned at their opposite ends to fit around the depending flange A² to which they are secured by welding. Also the members B extend obliquely across the member A and are spaced farther apart at the rear edge of said member and closer together at the front edge. The members B are themselves preferably formed of pressed sheet metal and in addition to the depending side flanges B', which form the channel cross section, the web portion B² may be provided with one or more beads B³. The specific construction of the hinge C is not a part of the instant invention but, as diagrammatically illustrated, one member of each hinge is secured to the depending portion B⁵ of the reinforcement member B so that the load of the cover is transmitted through such reinforcement member directly to the hinge. The lower edge of the depending flange A² is preferably return bent as indicated at A³ and is then extended horizontally inward to form a flange A⁴. D is a lining member for the lid preferably formed of pressed plastic material and having its marginal portions secured

2

to the flange A⁴. As shown the lining member D has a central portion D' depressed below the level of the flange A⁴ and an upwardly and outwardly inclined marginal portion D² extending to the point of attachment to said flange. There is also a sealing gasket E secured to the flange A⁴. Preferably this gasket E is a tubular member of rubber or similar material provided with an angular shank portion E' which is secured in the angle between the portions A³ and A⁴. Thus, when the lid is sealed on a cabinet such as F, the tube E will be slightly deformed to obtain an effective seal around the entire margin of the cover and a horizontal flange E² of the angle shank portion E' can be secured between the members E and flange A⁴ to complete the sealing connection with the latter.

At the front edge of the lid is a handle G, the construction of which is not a part of the instant invention. However, to transmit stresses from this handle to the lid an angle cross section reinforcement member H is secured to and extends along the inner face of the flange A² at the front side of the lid.

To produce effective thermal insulation, the space between the member A and the liner D is filled with a suitable loose insulating material represented by I.

To provide illumination for the interior of the refrigerator when the lid is open, a lamp bulb J is located inside of the lid to register with a transparent window K. This bulb is connected into an electric circuit including a switch member L, having a depending knob or actuating member L' which, when the lid is seated, will be actuated by an adjacent portion L² of the cabinet to break the circuit to the lamp. On the other hand when the lid is raised the switch L will automatically return to closed position for effecting illumination of the bulb.

The pressed sheet metal member A is preferably fashioned with its top portion A' slightly dished in an upward direction but the reinforcing members B are rectilinear. This forms in the assembly a space B⁴ between the top A' and the member B. Preferably a damping pad I' of suitable insulating or sound deadening material is located in the space B⁴ to prevent metal to metal contact and thereby prevent objectionable noise.

As shown in Figure 3, each of the hinges C has a hinge part C' disposed in surface to surface relation with the outer side of depending flange A² with a washer M disposed between said hinge part and flange. Also as shown, the down-turned end portion B⁵ of each channel-shaped

reinforcing member B is disposed with the base or web portion B² thereof in surface to surface relation with the inner side of depending flange A².

Common securing means are provided at each hinge connection for securing the cover to the respective hinge parts C'. Said securing means are in the form of suitable bolts N which extend through hinge part C', washer M, base B² and depending flange A², and which, in cooperation with nuts P, serve to hold the same together. Thus the load of the panel or cover will be transferred through each reinforcing bar B directly to the hinges, thereby avoiding distortion of the cover.

With the construction as above described the lid can be readily swung upward on its hinges to provide access to the cabinet and, when returned to seated position, will produce an effective air seal around its entire margin.

What I claim as my invention is:

1. The combination with a refrigerator cabinet having an opening, of a closure for said opening having a cover portion comprising a relatively light gauge sheet metal panel having a marginal depending flange, and means for reinforcing said light gauge sheet metal panel, including a channel-shaped metal bar extending across the underside of said panel and having downturned end portions upon the inner sides of the depending marginal flange of said panel, the base of said channel-shaped bar being rigidly secured in surface to surface relation to said depending marginal flange of said panel at opposite edges thereof.

2. The combination with a refrigerator cabinet having an opening, of a closure for said opening having a cover portion comprising a relatively light gauge sheet metal panel having a marginal depending flange, means for reinforcing said light gauge sheet metal panel, including a bar extending across the underside of said panel and terminally secured in surface to surface relation to said depending flange at opposite edges of said cover, and means for mounting said closure upon a refrigerator cabinet, including a hinge having a part secured to said depending flange and portion of said bar in surface to surface relation thereto.

3. The combination with a refrigerator cabinet having an opening, of a closure for said opening having a cover portion comprising a relatively light gauge sheet metal panel having a marginal depending flange, means for reinforcing said light gauge sheet metal panel, including a channel-shaped metal bar extending across the underside of said panel and having downturned end portions upon the inner sides of the depending marginal flange of said panel, the base of said channel-shaped bar being rigidly secured in surface to surface relation to the inner side of said depending marginal flange, a hinge for said closure having a part upon the outer side of said depending marginal flange, and means securing said hinge in assembled relation with said closure, including a fastening element extending through said depending flange and the base of said channel-shaped bar.

4. The combination with a refrigerator cabinet having an opening, of a closure for said opening having a cover portion comprising a relatively light gauge sheet metal panel having a marginal depending flange, means for reinforcing said panel, including a pair of laterally spaced bars extending across the underside of said panel

and having downturned end portions secured to the inner side of said depending marginal flange at longitudinally spaced points thereof, and means for mounting said closure upon a refrigerator cabinet, including hinges upon the outer side of said depending flange and respectively secured to said downturned end portions of said bars.

5. The combination with a refrigerator cabinet having an opening, of a closure for said opening having a cover portion comprising a relatively light gauge sheet metal panel having a marginal depending flange, means for reinforcing said panel, including a pair of laterally spaced bars extending across the underside of said panel and having downturned end portions secured to the inner side of said depending marginal flange at longitudinally spaced points thereof, and means for mounting said closure upon a refrigerator cabinet, including two hinges having parts upon the outer side of said depending flange at spaced points corresponding to the spaced points aforesaid of the end portions of said bars, and means securing said hinges to said closure including fastening elements extending through said depending flange and said downturned end portions of said bars.

6. The combination with a refrigerator cabinet having an opening, of a closure for said opening having a cover portion comprising a relatively light gauge sheet metal panel having a marginal depending flange, means for reinforcing said light gauge sheet metal panel, including a channel-shaped metal bar extending across the underside of said panel and having downturned end portions upon the inner sides of the depending marginal flange of said panel, the base of said channel-shaped bar being next to and cooperating with the underside of said panel to form a pocket, and a damping pad in said pocket and preventing metal to metal contact between said bar and said panel.
